UNITED STATES PATENT OFFICE.

PAUL A. WEYAND, OF MAYWOOD, ILLINOIS, ASSIGNOR TO ELECTRIC SERVICE SUPPLIES COMPANY, OF CAMDEN, NEW JERSEY, A CORPORATION OF NEW JERSEY.

ELECTRIC-MOTOR-CONTROLLER REGULATOR.

No. 12,744.

Specification of Reissued Letters Patent. Reissued Jan. 28, 1908.

Original No. 110,940, dated January 16, 1906, Serial No. 265,215. Application for reissue filed March 18, 1907. Serial No. 363,157.

To all whom it may concern:

Be it known that I, PAUL A. WEYAND, a citizen of the United States, residing in the village of Maywood, county of Cook, and State of Illinois, have invented a new and useful Improvement in Electric-Motor-Controller Regulators, of which the following is a specification.

My invention relates to that class of devices designed to automatically regulate the movement of the controller of electric motors.

The object of my invention is to provide an automatic regulator of cheap and simple construction that by direct and positive action retards the movement of the controller while the current is being turned on, that can be easily attached to the controller in common use, that can be timed in its movements automatically and its operative parts be perfectly lubricated.

The manner in which I accomplish my objects is described in the following specification, and illustrated in the accompanying drawings, in which

Figure 1 is a side elevation showing the regulator in position on the controller-casing. Fig. 2 is a top plan view of the regulator, the controller-casing not being shown. Fig. 3 is an enlarged top view of the timing device looking into the box. Fig. 4 is a diagrammatic view of the interior of the base of the regulator, showing the construction and movements of the mechanism. Fig. 5 is a vertical sectional view on the line 5, 5, Fig. 2, looking in the direction of the arrows. Fig. 6 is an interior plan view of the cover or top part of the regulator, showing the position, mode of attachment of the pawl to the cover, and limit of its movement. Fig. 7 is a vertical sectional view on the line 7, 7, Fig. 5 looking in the direction of the arrows, showing the attachment and position of the pawl and its connection with the timing mechanism. Fig. 8 is a sectional view of the pawl on the line 8, 8, Fig. 7, looking in the direction of the arrows, showing the spring mechanism by which it is held in position on the pivot affixed in the cover. Fig. 9 is a detailed view of the pivot-stud on which the pawl is secured. Fig. 10 is a cross-section of the same parts on the line 10, 10, showing the recess therein. Fig. 11 is an enlarged sectional view of the air-valve forming part of the time mechanism. Fig. 12 is a sectional detailed view showing the manner in

which the cover is attached to the base of the regulator.

In the drawings, A represents the controller-casing in use on trolley-cars. On this casing the base B of the regulator is secured by screws or by other suitable means. On this base and forming a part thereof is a vertical cylindrical part B², in which there is an external peripheral channel B³. In the inside of the part B² and forming part thereof are two series of ratchet teeth forming stops B⁴ and B⁵, the number and relative position of these teeth corresponding with the number and position of "points" in the controller. In the center of the base is a cylindrical aperture B⁶, its wall B⁷ extending the same height as the part B². Midway between the series of the ratchet-teeth and wall B⁷ are two series of tetragonal cam-studs C and C¹. These studs correspond in number and relative position with the ratchet-teeth and form an integral part of the base.

Over the cylindrical part B² and the interior of the base a cover D is fitted, the outside vertical part covering the channel B³ in the cylindrical part B². This cover is secured on the base by two clips D¹, which are secured in the recesses D² in the cover D. The lip or lug D³ of each of these clips fits into the channel B³. Thus attached the cover is free to be revolved on the base. In the center of the cover is a cylindrical aperture E. The wall E' of this aperture extends into the aperture B⁶ in the base. On the top of the cover and forming part thereof is a radial jaw F, adapted to receive the shank of the controller-handle G, which is thereby connected with the cover and by said connection the cover is revolved. Through the aperture E the controller-rod G' extends. On this rod the handle G is placed.

Affixed in the boss H, forming part of the cover, is a pivot-stud I, which projects on the inside of the cover into the interior of the base B. In this stud is a countersunk recess I' and center hole I². The vertical center of this recess corresponds with the line of an imaginary circle having its center in the center of the cover and passing through the studs C and C¹. On this pivot is a pawl J. The pivot-hole J' of the pawl is slightly oblong, its greatest diameter being in the direction of the length of the pawl. From this pivot-hole J' a pin-hole J² extends horizontally into the length of the pawl. In this hole a

spring J^3 is placed and against the spring a pin J^4 . The pointed end of this pin is forced by the spring into the center of the recess I' and thereby holds the pawl on the stud and 5 forces the pawl back to its normal position J^5 from the positions J^6 and J^7 , as shown in Fig. 6, and holds it there at all times when the pawl is free from engagement with the ratchet-teeth and studs C and C' . The pressure 10 sure of this spring and pin on the pawl and pivot-stud holds the pivot end of the pawl close to the pivot-stud as shown in Figs. 6 and 8. On the underside near the free end of the pawl is an oval post J^8 , as shown in Figs. 4, 6 and 7. On the top of the pawl is 15 an arm K , which extends through a slot K' , in the cover, in which it is free to move. To the upper part of this arm two cups K^2 and K^3 are attached, the cup K^3 being perforated, as shown at K^7 , Fig. 5. These cups and arm are covered by a box K^4 , which is affixed on the cover D . This box is provided with a lid K^5 and an air-valve K^6 , as shown in detail in Fig. 11.

When the regulator is constructed as described and illustrated in the drawings and attached to the controller, its operation and the movement of its several parts are as follows: The handle G is placed on the controller-rod G' , which projects through the aperture E in the cover D , the shank of the handle resting in the jaw F , as shown in Figs. 1 and 2 and in position ready to be moved to turn on the electric current. In 30 this position the pawl is free from contact with the ratchet-teeth and studs in the base and is held at rest in the normal position J^5 (see Figs. 4 and 6). The movement of the handle in the "on" direction, that is, to turn 35 on the current, revolves the cover and pawl in the direction of the arrow M (see Figs. 2 and 4), and as this movement continues the post J^8 on the pawl strikes the end of the first stud in the series C and slides along its 40 outer face. This contact of the post and stud forces the free end of the pawl outward from its normal position J^5 to the position J^6 and into engagement with the first of the ratchet-teeth in the series B^4 and stops the 45 movement of the controller at the first point. The force of the contact of the pawl and tooth is transferred through the pivot end of the pawl to the stop-block L . The oblong pivot-hole in the pawl prevents this force 50 acting on the pivot-stud and allows it to force the pin J^4 back on the spring J^3 , which is thereby compressed. Before the controller can be moved to the next point the handle must be slightly reversed so as to release 55 the nose of the pawl from contact with the ratchet-tooth. When this is done, the pressure of the spring J^3 , forces the pin J^4 into the center of the recess I' in the pivot I . This force moves the pawl back to the normal 60 position J^5 , and places the post J^8 be-

tween the ends of the first and second studs in series C . The controller can then be moved forward again, the post J^8 striking the end and sliding along the outer face of the second stud, the pawl being thereby forced outward into the position J^6 and into contact with the second ratchet-tooth in the series B^4 , the controller being thereby stopped at the second point. The handle is again slightly reversed, the pawl resumes its normal position again, and the controller can be then moved to the third point. These movements can be repeated till each of the ratchet-teeth in both series have been engaged by the pawl and all the points have been made by the controller and the full current thereby turned on. The reverse movement of the controller in the direction to the arrow N , whereby the current is cut off, can be made at any point in the revolution of the handle, rod and regulator-cover. When the reverse movement begins, after the pawl-post J^8 has passed one or more of the studs in the series C or C' , the post strikes the reverse end of the nearest stud and slides 90 along the inside face of the stud, thereby forcing the pawl to the inside position J^7 , as shown in Fig. 4, and out of all possible contact with the ratchet-teeth or other part of the interior of the base. It will be seen that 95 during the movement of the controller handle in the "on" direction the part of the pawl which is engaged by the cams or studs C and C' , that is, the pawl-post J^8 , travels in a path or way outside of the said studs, between the studs and the ratchet-teeth, while during the reverse movement of the handle the said part travels in a path or way inside, that is, at the opposite side of the studs, the latter then holding the pawl out of contact 100 with the ratchet-teeth or stops. If it is desirable to retard the movement of the pawl from the outer position J^6 back to the normal position J^5 , and thereby time the movement of the controller from point to point, it can be accomplished by providing the pawl with the arm K , cups K^2 and K^3 , slot K' in the cover, and a box K^4 . With the regulator so constructed each forward movement of the controller-rod, handle, cover and pawl 110 compresses the cup K^2 and expels the air from within the cup through the air-valves K^6 , tends to create a vacuum in the cup and retards the movement of the pawl till that 115 vacuum is destroyed by the flow of air through the air-valve. This flow of air can be regulated by the adjustment of the air-valve. The cup K^3 when compressed by the reverse movement simply assists the action of the spring J^3 and pin J^4 in forcing the pawl from 120 the position J^7 back to the position J^5 . The interior of the base may be filled with 125 a suitable lubricant to reduce the friction of the moving parts, the cylindrical part B^2 and wall B^7 of the base and the cover D and the 130

wall E' being sufficient to retain the lubricant within the base.

It is obvious that the arm K, cups K², K³, box K⁴, and air-valve K⁶ may be dispensed with without materially affecting the efficiency of my regulator, and I therefore do not limit myself to its use on my improvement.

What I claim as new, and desire to secure by Letters Patent, is:

1. In an electric controller-regulator of the kind described, the combination of a main body having a base B, a cylindrical part B², a series of interior ratchet-teeth B⁴ and B⁵, a series of studs C and C', and a central aperture B⁶, said body being adapted to fit over an electric controller-rod and to be affixed to a controller, with a revoluble cover, D, having a central aperture E, a jaw F, adapted to receive the shank of a handle of an electric controller; and a pawl J, pivotally attached to the inside of said cover, said pawl being adapted to be engaged by the studs C and C', and to be deflected thereby into engagement with said ratchet-teeth; and means for returning said pawl from its deflected position to a normal position J⁶, substantially as described and for the purposes specified.

2. In an electric-controller-regulator of the kind described a main body having a base B, a cylindrical projection B², a series of interior ratchet-teeth B⁴ and B⁵, a series of studs C and C' and an aperture B⁶, with a cover, D having a central aperture E and a jaw F; means for securing said cover on the base part B², and of permitting the cover to be revolved thereon; and a pawl J, pivotally supported in said cover, said pawl having a post J⁸, adapted to be engaged by the studs, C and C', and the pawl be thereby deflected when the cover is revolved, and means for returning said pawl from the deflected position to the normal position of rest J⁶, substantially as described and for the purposes specified.

3. In an electric-controller-regulator of the kind described the combination of a main cylindrical body, having interior ratchet-teeth, studs and a central aperture, with a revoluble cover, having a central aperture E, a jaw F, and a stop-block L, and a pawl J, pivotally supported in said cover, said pawl being adapted to be engaged by the stud C and C' in the said main body, and to be deflected thereby into engagement with the said ratchet-teeth when said cover is revolved; and means for returning said pawl from its deflected positions to a normal position J⁶, substantially as described and for the purposes specified.

4. In an electrical controller-regulator of the kind described, the combination of a main cylindrical body having a series of interior ratchet-teeth and a series of studs C

and C', and a central aperture B⁴, and a cover D, adapted to fit and to be revolved on said main body, said cover having a central aperture E, a jaw F, and stop-block L; with a pawl J, pivotally supported in said cover, said pawl being adapted to be engaged by the said studs and to be deflected thereby into engagement with the said ratchet-teeth when said cover is revolved on said main body; and means for returning said pawl when so deflected to a normal position of rest J⁶; substantially as described and for the purposes specified.

5. In an electric controller of the kind described the combination of a main cylindrical body having a series of interior ratchet-teeth, a series of studs and a central aperture B⁶, and a cover D, adapted to fit and be revolved on said main body, said cover having a central aperture E, a jaw F and a stop-block L; with a pawl J pivotally supported in said cover, said pawl having a post, J⁸, adapted to be engaged by the said studs, and to thereby deflect said pawl into engagement with the said ratchet-teeth when said cover is revolved on said main body; and means for returning said pawl when so deflected, to a normal position of rest; substantially as described and for the purposes specified.

6. In an electric controller-regulator of the kind described, the combination of a main cylindrical body having a series of interior ratchet-teeth, a series of studs and a central aperture, and a cover D, revolvably attached to said main body, said cover having a central aperture E, a jaw F, a stop-block L, and a pivot-stud I, said stud having a countersunk recess, I', with a pawl J, adapted to be supported on said pivot-stud, said pawl being provided with a spring J³, and a pin J⁴, actuated by said spring, and being thereby forced into the recess I' in the pivot-stud I, said spring and pin being adapted to hold said pawl in a position of rest on said pivot-stud, and to return it to said position when deflected therefrom; substantially as described and for the purposes specified.

7. In an electric controller-regulator of the kind described the combination of a main cylindrical body having a series of interior ratchet-teeth, a series of studs C and C', a central aperture B⁶; and a cover D, revolvably attached to said main body, said cover having a central aperture E, a jaw F, a stop-block L, and a pivot stud I, with a pawl J, supported on the said pivot-stud, said pawl having an arm K, extending through a suitable slot K' in the cover D, and a pair of cups K² and K³, attached to said arm and a box K⁴, covering said cups and arm; said box being provided with an air-valve K⁶, and being attached to said cover; substantially as described and for the purposes specified.

8. The combination with an electric con-

troller of a controller-regulator herein described, comprising a main body having a series of ratchet-teeth, a series of studs, and a central aperture, said body being provided 5 with a cover revolubly secured thereon, said cover having a central aperture, a jaw, a pivot-stud and stop-block, and a pawl supported on said pivot-stud, said pawl being adapted to be engaged by said studs and to 10 be thereby deflected into engagement with said ratchet-teeth; and means for returning said pawl from the deflected positions to a position of rest; and means for regulating the time of the movement of said pawl from 15 engagement with said teeth to a position of rest; substantially as described and for the purposes specified.

9. The combination with an electric controller of a controller-regulator, herein described, comprising a main body having a series of ratchet-teeth, a series of studs, and a central aperture, and a cover revolubly secured on said main body, said cover having a central aperture, a jaw, a pivot-stud 20 and a stop-block, and a pawl supported on said pivot-stud, said pawl being adapted to be engaged by said series of studs, and to be thereby deflected when said cover is revolved and means for returning said pawl from the 25 deflected positions to a position of rest; substantially as described and for the purposes specified.

10. In a controller regulator, the combination with a series of stops, a rotatable member having a pawl movable only in one plane, a series of cams for moving the pawl into engagement with the stops during movement of the member in one direction, and provision for preventing engagement of the pawl 30 with the stops during movement of the said member in the opposite direction.

11. In a controller regulator, the combination with a series of stops, a rotatable member having a pawl movable only in one plane, a series of cams for moving the pawl into engagement with the stops to effect a step by 35 step movement of said member in one direction, and provision for permitting uninterrupted movement of the said member in the 40 opposite direction.

12. In a controller regulator, the combination with a handle, of a pawl movable with and also independently of the handle, said independent movement being only in a horizontal plane, a series of stops, a series of cams for moving the pawl into engagement with the stops when the handle is turned in one direction, and provision for permitting uninterrupted movement of the handle in the 50 opposite direction.

13. In an electric controller regulator, the combination with a series of stops, a rotatable member, a one piece pawl pivoted to said member, and a series of cams arranged to 55 move said pawl on its pivot to deflect the

same into engagement with the stops when the said member is moved in the "on" direction, and to hold said pawl out of contact with the stops when the member is moved in the reverse direction.

14. In an electric controller regulator, the combination with a base having a series of stops, a rotatable member associated with said base, a pawl connected to said member by a single pivot, and means to move said pawl on its pivot to deflect the same into engagement with the stops when the said member is moved in one direction and to hold the pawl out of contact with the stops when the member is moved in the reverse direction. 75

15. In an electric controller regulator, the combination with a base having a series of stops and cam studs, a rotatable member mounted over said base, a pawl pivoted to said member and cammed by the studs into engagement with the stops to intermittently arrest the said member when moved in the "on" direction and held by the said studs out of contact with the stops when the member is moved in the reverse direction. 80

16. In a controller regulator, the combination with a controller, a base mounted thereon having a series of stops, a rotatable cover having a pawl and adapted to move with the controller shaft, and a series of studs for moving the pawl into engagement with the stops during the movement of the shaft in the "on" direction and for holding the pawl out of engagement with the stops during movement of the shaft in the reverse direction. 95

17. In an electric controller regulator, the combination with a series of fixed cams, a series of stops, a rotatable member, and a pawl carried by the rotatable member and adapted during the turning on movement to be deflected by the cams into engagement with the stops, the part of the pawl engaged by the cams during such movement traveling in a path between the cams and the stops 110 and during reverse movement traveling in a path at the opposite side of the cams.

18. In an electric controller regulator, the combination with a rotatable member having a pawl, of a series of stops, and a series of cams which during movement of the member in one direction deflect the pawl into engagement with the stops and in the reverse direction deflect the pawl away from the stops. 115

19. In a controller regulator, in combination, a base having a series of stops, a rotatable cover for the base having a pawl, a series of cams on the base which during movement of the cover in one direction deflect the pawl towards and into engagement with the stops and which in the reverse direction deflect the pawl in the opposite direction and away from the stops, and a handle for moving the cover. 125

20. In an electric controller regulator, the combination with a rotatable member having a pawl, of a series of stops, and a series of cams which during movement of the member in one direction deflect the pawl into engagement with the stops and in the other direction deflect the pawl away from the stops, and a spring for centering the pawl with respect to the cams.
- 5 21. In an electric controller regulator, in combination, a base, a rotatable cover therefor, means to regulate the movement of said cover, and coöperating means between the cover and base for securing the parts together while permitting rotation of the cover.
- 10 22. In a controller regulator, in combination, a base, a rotatable cover, means carried by one of said parts and coöperating with the other to prevent separation of said parts without interfering with the rotation of the cover, and means for compelling intermittent movement of the cover in one direction while permitting uninterrupted movement thereof in the opposite direction.
- 15 23. In an electric controller regulator, in combination, a base, a rotatable cover therefor, means to intermittently arrest the movement of said cover, and coupling means carried by the cover and engaging the base to secure the cover and base together without interfering with the rotation of the cover.
- 20 24. In a controller regulator, in combination, a base adapted to be mounted on a controller casing about the controller shaft, a rotatable cover for the base, means on one of said parts and engaging the other to connect the same and prevent separation thereof without interfering with the rotation of the cover, and means carried by one of said parts
- 25 40 and coöperating with the other to intermittently arrest the movement of the cover in one direction without interfering with its movement in the reverse direction, and a handle for moving the cover.
- 45 25. In a controller regulator, the combination with a base, a rotatable cover, means for compelling intermittent movement of the cover in one direction while permitting uninterrupted movement thereof in the opposite direction, and means for connecting the cover directly to the base to prevent separation thereof without interfering with the rotation of the cover.
- 50 26. In an electric controller regulator, in combination, a stationary base provided with a series of stops and a series of cams, a rotatable cover for the base having a pawl coöperating with the cams and stops to intermittently arrest the movement of the cover, and means for securing the cover and
- 55 60 base directly together to prevent separation of the parts, while not interfering with the rotation of the cover.
27. In an electric controller regulator, in combination with the controller shaft and casing, a base supported by the casing and having a channel, and a cover on the shaft and having a lug engaging said channel.
- 65 28. In an electric controller regulator, the combination with a controller, of a base mounted thereon, a rotatable member on the base, means for regulating the movement of the said member, operating means for connecting the controller rod and member, and means for connecting the base and rotatable member together without interfering with the rotation of the said member.
- 70 29. In an electric controller regulator, the combination with a controller, of a base mounted thereon and provided with cams and stops, a rotatable cover on the base having a pawl which coöperates with the cams and stops to intermittently arrest the cover, a jaw on the cover, an operating handle engaging the controller rod and jaw to connect said rod and cover, and a coupling to secure the cover on the base without interfering with its rotation.
- 75 30. In a controller regulator, the combination with a base having a series of stops and a series of cams formed thereon, of a rotatable member mounted upon said base, a dog carried by said member adapted to engage said cams and said stops, and means for connecting said rotatable member to said base to prevent a vertical movement thereof without preventing the rotation of the same.
- 80 31. In a controller regulator, the combination with a base having a series of stops and a series of cams formed thereon, a projection formed upon said base having an annular channel therein, a rotatable member, a dog mounted thereon adapted to engage said cams and said stops, and a projection formed thereon adapted to engage said annular channel, whereby a vertical movement of said member is prevented without preventing the rotation thereof.
- 85 32. In a controller regulator, the combination with a base having a series of stops and a series of cams formed thereon, of a rotatable member, a dog mounted thereon adapted to engage said cams and said stops, and means for connecting said member to said base to prevent a vertical movement of said member without preventing the rotation thereof.
